UNITED STATES PATENT OFFICE

MAURICE H. WENNING, OF QUINCY, ILLINOIS

DESIGN FOR AN AUTOMOBILE

Application filed October 2, 1930. Serial No. 37,112. Term of patent 7 years.

To all whom it may concern:

Be it known that I, MAURICE H. WENNING, a citizen of the United States, residing at Quincy, in the county of Adams and State of Illinois, have invented a new, original, and ornamental Design for Automobile, of which the following is a specification, reference being had to the accompanying drawing, forming part thereof.

Fig. 2 is a rear elevation thereof,
Fig. 3 is another perspective view thereof.
I claim:

The ornamental design for an automobile as shown.

MAURICE H. WENNING.
